UNITED STATES PATENT OFFICE.

JOHN J. MEYER, OF NEW YORK, N. Y.

INSERTABLE JOINT.

Application filed September 27, 1924. Serial No. 740,333.

To all whom it may concern:

Be it known that I, JOHN J. MEYER, a citizen of the United States, and a resident of the city of New York, borough of Manhattan, in the county and State of New York, have invented a new and Improved Insertable Joint, of which the following is a full, clear, and exact description.

This invention relates to insertable joints for soil pipes and the like and has for an object to provide an improved construction which is formed of a minimum number of parts and which may be readily mounted in place without injury to the pipe above or below the joint.

Another object of the invention is to provide an improved construction which may not only be readily placed in position but which may be placed in position without disturbing the lower part of the soil pipe or the upper part while presenting a proper support for the upper part and a substantially continuous water-tight pipe structure.

A still further object of the invention is to provide a structure wherein shiftable means are provided for supporting a superimposed pipe section at different points.

A still further object of the invention is to provide an insertable joint which is in part a continuation of my co-pending application, Serial No. 708,811.

In the accompanying drawing—

Figure 1 is a fragmentary elevation of part of a soil pipe line arranged in a building, certain parts being broken away for better illustrating the construction.

Figure 2 is a side view of the upper end of the inserted pipe section shown in Figure 1.

Figure 3 is a sectional view through Figure 2, on line 3—3.

Figure 4 is a transverse sectional view on line 4—4 of Figure 2.

Figure 5 is a view similar to Figure 4 but disclosing a slightly modified construction.

Figure 6 is an enlarged fragmentary view of a set screw and associated parts embodying certain features of the invention.

Figure 7 is a fragmentary vertical sectional view through an inserted joint and the lower end of the superimposed pipe, the same disclosing a modified construction to that illustrated in Figure 1.

Referring to the accompanying drawing by numerals, 1 indicates part of a building

and 2 the soil pipe line. In order to put an extra section, as for instance, the Y section 3, it is necessary to remove one of the sections of the line 2 and in removing the same the section is usually broken. As the various sections of line 2 have bells or hubs, an ordinary section cannot be placed in position unless all the superimposed pipe sections are removed or raised, which is usually impossible. To obviate this necessity, a single inserted pipe section 4 is provided and is made of a special construction whereby it may be readily inserted and certain parts thereof adjusted to cause a proper support of the superimposed pipe sections arranged above the section 4. It will also be noted that the Y section 3 is of usual construction provided with a hub or bell 5 and the lowermost pipe section 6 of the superimposed section of the pipe line 2 is also of the usual construction having a bell or hub 7 and a straight body adapted to fit into the hub or bell 9 of section 4. The lower end of section 4 is fitted into the hub 5 in the usual manner but before this is done the hub 9 is telescoped over the lower end of section 6 until the lower end of section 4 may be swung over the hub 4. After this has been done the parts are lowered into the position shown in Figure 1 while the sections 6 and other superimposed sections are supported by a wire or in any desired manner temporarily.

The removable abutment or bar 10 is moved into position as shown in Figures 1, 3 and 4 beneath the lower end of the section 6 whereupon said section is properly supported and the temporary supports connected with said section may be removed. Instead of arranging the abutment bar 10 in the upper recess 11, it might be positioned in the lower recess 12 in case the lower end of the pipe section 6 extends downwardly past the opening 11. In order to assist the abutment bar 10, a supporting screw 13 is provided which is formed with a reduced smooth supporting surface 14 adapted to engage and support part of the weight of the pipe 6. If desired, the screw 13 could be supplied with a gasket 15 and a lock nut 16 whereby an air-tight connection may be secured. Preferably, the screw 13 is positioned diametrically opposite the abutment bar 10 though it could be arranged at some other position if desired.

As indicated particularly in Figures 2 and

3, the abutment bar 10 is provided with a long smooth section fitting into the bores or recesses 12, one of which is formed with a threaded section for receiving a threaded enlargement 17 of bar 10. A squared end 18 is provided on the abutment bar 10 for receiving a wrench. Associated with the abutment bar 10 is a plug 19 which is similar in shape and construction to the enlargement 17 but merely acts to close either of the passage-ways 11 and 12. It is, of course, evident that the screw 13 may be used or may not be used as desired, though ordinarily one of these screws is desirable as it presents a more even support for the pipe section 6. It will also be noted that both the screw 13 and the bar 10 are positioned to be out of the direct line of the bore of section 6 whereby there will be an unobstructed passage-way. The bar 10 and screw 13 also present in a certain sense a false bottom for receiving oakum, waste or other similar material 20 above which is arranged the packing lead 21 for making a gas-tight joint.

25 In Figure 5 a modified form of the invention is shown wherein abutment bars 22 and 23 are provided, said bars being similar to the bar 10 but instead of being arranged in vertical alignment they are arranged in horizontal alignment and thus present a support on diametrically opposite sides of the pipe section 6.

In Figure 7 another modified form of the invention is shown wherein the inserted pipe section 4 is provided with a solid bell 9 of any desired construction provided it is formed with one or more threaded bores 24 for receiving the screw 25. From an examination of this figure it will be noted that the screw 25 is almost parallel with the side walls of the pipe section 4 though sufficiently inclined to project therein to provide a proper support for the pipe section 6 and yet permit the pipe section to be adjusted vertically upon the rotation of the screw 25.

What I claim is:

1. An insertable joint for soil pipes and the like, comprising a pipe section having a body and a hub, said hub having a pair of vertically aligned apertures partly merging into the bore of said hub, each of said apertures having an enlarged threaded portion, a rod having an enlarged threaded portion fitted into one of said apertures, the threaded portion of said rod being screwed into the threaded portion of said aperture, and a threaded plug being threaded into the enlarged threaded portions of the other apertures, said apertures being of the same size and shape and the threaded plug being of the same size and shape as the enlarged threaded portion of said rod whereby they may be transposed to cause said rod to act as a support at different heights for a superimposed pipe section.

2. An insertable joint for soil pipes and the like, comprising a pipe section having a body and an elongated hub at one end, said hub being provided with a pair of vertically aligned sockets or passage-ways, each socket or passage-way being formed with a threaded section, and an abutment bar having a threaded section, said abutment bar being adapted to fit into either of said sockets and screwed into the threaded section, said socket being so positioned that the abutment bar will present an abutment or support for the lower end of a superimposed pipe line, the course of said sockets or passage-ways and abutment bar being tangential to the bore.

3. In an insertable joint for soil pipes and the like, a pipe section formed with a body, and an elongated hub, said hub being provided with a plurality of sockets or openings positioned at different heights for receiving an abutment bar, the course of said sockets and abutment bar being tangential to the bore, and means for making said sockets watertight.

4. In an insertable joint for soil pipes and the like, a pipe section formed with a body and an elongated hub, said hub being provided with a plurality of vertically aligned bar receiving sockets, and a threaded aperture for each socket arranged in the same plane, one of said threaded apertures being adapted to receive a supporting screw to support a superimposed pipe, the course of said sockets and supporting screw being tangential to the bore.

5. An insertable joint for pipes, comprising a pipe section having a telescoping hub adapted at its upper end for a filler joint, two or more threaded apertures in the wall of said hub extending into the bore of said hub, each aperture being positioned at a different level in said hub, a screw plug in one of said apertures having a supporting portion or member projecting into said hub bore for supporting a superimposed pipe from beneath the end of said pipe, and a non-supporting screw plug or plugs fitted in the remaining apertures, said supporting screw plug being positioned selectively in one of said apertures to form a support at a variable height.

6. An insertable joint for pipes, comprising a pipe section having a telescoping hub adapted at its upper end for a filler joint, a threaded aperture in the wall of said hub extending into the bore of said hub, a long supporting screw member threaded into said aperture and extending into the bore a considerable distance for supporting a superimposed pipe, said distance being more than the thickness of the wall of said superimposed pipe and the course of said aperture and said screw member being tangential to the bore whereby a greater area

of the foot wall of said superimposed pipe is rested upon said long screw member, and means on said hub on the same plane as the screw member for giving added support 50 to the other side of said superimposed pipe from beneath.

7. An insertable joint for soil pipes and the like, comprising a pipe section having a telescoping hub adapted at its upper end for 55 a filler joint, an aperture in the wall of said hub extending into the bore of said hub, a supporting member inserted through said aperture and extending into said bore for supporting a superimposed pipe, the course 60 of said aperture and supporting member being tangential to said bore, said supporting member being positioned to support said superimposed pipe from underneath the end of said superimposed pipe, and threaded 65 means for making said aperture watertight.

8. An insertable joint for pipes, comprising a pipe section having a telescoping hub adapted at its upper end for a filler joint, a 70 transverse groove in the wall of said hub merging into the bore of said hub, an aperture in the wall of said hub merging into said groove, a socket in the wall of said hub merging into said groove at the end 75 of the groove opposite the aperture, a long supporting member adapted to be inserted through said aperture and extending into the socket, the course of said aperture, supporting member and socket being tangential 80 to said bore, said supporting member being adapted to support a superimposed pipe from underneath the end of the pipe, and means for making said aperture watertight.

9. An insertable joint for pipes, comprising a pipe section having a telescoping hub adapted at its upper end for a filler joint, an aperture in the wall of said hub extending into the bore of said hub, a long supporting member in said aperture and extending into the bore a considerable distance 85 for supporting a superimposed pipe, said distance being more than the thickness of 90 the wall of said superimposed pipe and the course of said aperture and said supporting member being tangential to said bore whereby a greater area of the foot wall of said superimposed pipe rests upon said supporting member.

10. An insertable joint for soil pipes and the like comprising a pipe section formed 55 with a body and an elongated hub adapted at its upper end for a lead filler joint, said hub being provided with a plurality of threaded openings positioned at different heights for receiving selectively a supporting member for supporting a superimposed pipe at variable heights, the remaining 60 threaded openings receiving non-supporting plugs.

11. An insertable joint for soil pipes and 65 the like, comprising a pipe section having a telescoping hub adapted at its upper end for a filler joint, an aperture in the wall of said hub extending into the bore of said hub, said aperture having a threaded portion, a 70 supporting screw threaded into said threaded aperture and extending into said bore for supporting a superimposed pipe, the course of said aperture and said supporting screw being tangential to said bore to prevent the 75 supporting screw from penetrating into the bore of the superimposed pipe and to align said bore of the superimposed pipe with the supporting member.

12. An insertable joint for soil pipes and 80 the like, comprising a pipe section having a telescoping hub adapted at its upper end for a filler joint, a transverse groove in the 85 wall of said hub, a supporting member supported in said groove, said member being actuated from the exterior of the wall of said hub to cause said member to be moved under the end of a superimposed pipe terminating in said hub and acting as a support therefor, the course of said groove and supporting member being tangential to the bore of said hub.

JOHN J. MEYER.
